UNITED STATES PATENT OFFICE.

JOHN E. HULTBERG, OF WARREN, PENNSYLVANIA.

VISE.

1,329,602.

Specification of Letters Patent.

Patented Feb. 3, 1920.

Application filed December 12, 1918. Serial No. 266,468.

To all whom it may concern:

Be it known that I, JOHN E. HULTBERG, a citizen of the United States, residing at Warren, in the county of Warren and State 5 of Pennsylvania, have invented certain new and useful Improvements in Vises; and I do declare the following to be a full, clear, and exact description of the invention, such as will enable others skilled in the art 10 to which it appertains to make and use the same.

The principal object of the present invention is to provide a vise whose jaws may be quickly and easily adjusted for work of different sizes, without the necessity of excessively turning a screw or the like; and a further object is to provide a novel means for swiveling the device upon a work bench or the like.

20 With the foregoing in view, the invention resides in the novel features of construction and the unique association of parts herein-after fully described and claimed, reference being made to the accompanying drawings 25 which form a part of this application.

Figure 1 is a side elevation of the device.

Fig. 2 is a top plan view thereof.

Fig. 3 is a central vertical longitudinal 30 section with parts in elevation.

Fig. 4 is a vertical transverse section on the planes indicated by the line 4—4 of Fig. 3.

Fig. 5 is a horizontal section as seen on the 35 plane of line 5—5 of Fig. 4.

Fig. 6 is a detail vertical transverse section on the plane of the line 6—6 of Fig. 3.

In the drawings above briefly described, the numeral 1 designates a preferably circular cast metal base having integral with its 40 upper side a vise body or block 2, the upper side of this block being provided with an elongated dove-tail rib 3 upon which a movable jaw 4 slides toward and away from a fixed jaw 5 which is integral with the block 2 and rises therefrom, being located at one end of the block while at the other end thereof, a detachable lug 7 extends upwardly, said lug being shown as provided with an opening 8 extending in a direction parallel with the rib 3 and preferably embodied in the form of a notch as shown.

A preferably rectangular rack bar 9 is slidably received in the notch 8 and in an opening 10 formed through the movable jaw 4, the front end of said rack bar having a screw

11 integral therewith and passing slidably through an opening 12 in the fixed jaw 5. A nut 13 is threaded on the screw 11 and is provided with a suitable handle 14 whereby the rack bar may be adjusted to tightly clamp the movable jaw 4 against the work after it has first been initially adjusted by the means yet to be described. The movement of the rack bar 9 is preferably restricted by means of the longitudinal slot 15 and the pin 16 received therein, said pin passing through the lug 7 as shown. Also, in order to return the rack to initial position and at the same time to withdraw the movable jaw 4 from the work when the nut 13 is loosened, a spring 17 is preferably provided, one end of said spring being received in a socket 18 in the lug 7, while its other end bears against an arm 19 which depends from the rear end 75 of the rack bar 9, said arm being by preference provided with a stud 20 received in said spring to retain it in place.

The teeth 21 of the rack bar 9 are preferably of the ratchet type seen most clearly in Fig. 3, and by means of these teeth and a pivoted dog 22, the movable jaw 4 may be connected with the rack bar for movement bodily therewith, the dog 22 being pivoted at 23 in a recess 24 formed in said movable jaw. It will be seen that by this arrangement, the dog 22 may be raised out of engagement with the teeth 21, whereupon the movable jaw 4 may be slid easily along the rib 3 or other guideway used, so as to bring it up 90 against the work W. After this initial adjustment, the handle 14 is operated to actuate the nut 13, so that the screw 12 and rack bar 9 come into play to force said movable jaw tightly against the work, through 95 the instrumentality of the dog 22. The moment the nut 13 is loosened, the spring 17 retracts all parts so that the work is released.

In mounting the device upon a work bench or the like, a swivel connection is preferably used, and to this end the circular base 1 rests upon a flat circular attaching plate 25 which is secured by screws or the like 26 to the bench or to any other suitable support, the upper edge of said plate 25 having a projecting continuous rib 27 on its periphery, while the base 1 is provided with an annular depending flange 28 which surrounds said rib 27 and is spaced outwardly therefrom as clearly shown in Figs. 4 and 5. A pair of bolts 29 pass through openings 30 in the base 1 and have their heads 31 located between

and in contact with the flange 28 and the peripheral edge of the plate 25, under the rib 27, and wing nuts or the like 32 are threaded on the upper ends of the bolts. It will be seen that the bolts not only provide a simple clamping means for securing the swiveled base in adjusted position, but their heads and bodies serve to center the base upon the plate 25. By removing the nuts 32, the entire base may be removed from the plate 25 and the bolts are then free from the latter. If desired, the previously used bolts or others may be passed directly through the openings 30 to secure the device to a work bench or the like when the plate 25 is not employed.

I claim:

In a vise mounting, a circular attaching

plate adapted to be secured to a support and having at the upper portion of its peripheral edge a continuous circumferential rib, a vise base resting on said plate and having a depending annular flange surrounding and spaced outwardly from said rib, said base having openings between the rib and flange, bolts passing through said openings with their heads located between and in contact with the peripheral edge of said attaching plate and said depending annular flange, said bolt heads being positioned under said rib, and nuts threaded on the upper ends of said bolts for clamping said base to said attaching plate when required.

In testimony whereof I have hereunto set my hand.

JOHN E. HULTBERG.
